(57) **CLAIM**

The ornamental design for a cordless drill station as shown and described.

DESCRIPTION

FIG. 1 is a front, right, perspective view of the cordless drill station in accordance with my design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof; and,
FIG. 8 is a front, top, left, perspective view thereof.
The broken lines illustrate portions of the environment which form no part of the claimed design.
